UNITED STATES PATENT OFFICE.

HARRY J. MOREY AND FAY A. BROGDEN, OF SYRACUSE, NEW YORK.

LAMP-SOCKET.

1,007,791.

Specification of Letters Patent. Patented Nov. 7, 1911.

Application filed July 9, 1909. Serial No. 506,931.

To all whom it may concern:

Be it known that we, HARRY J. MOREY and FAY A. BROGDEN, citizens of the United States, and residents of Syracuse, in the county of Onondaga and State of New York, have invented certain new and useful Improvements in Lamp-Sockets, of which the following is a specification.

This invention relates to lamp sockets, and in particular to the type in which the switch is operated by a cord or chain.

The objects of this invention are to provide a socket and switch which will be simple in construction and easily assembled.

15 The invention generally stated consists in a base provided with switch contacts connected in series with a circuit, in this case with lamp contacts, a movable contact plate adapted to bridge the switch contacts, and a ratchet member adapted to move the plate to bridge the contacts and close the circuit and move it to a position to open the circuit.

The ratchet member is operatively connected with a cord which moves it in one direction, and a spring is connected with the ratchet to move it in the opposite direction. This spring is a torsion spring which surrounds the pivot pin for the contact plate and the movable ratchet member, and performs the double function of moving the ratchet member in one direction and maintaining the contact plate operatively in engagement with the switch contacts. This spring is arranged so that its tension may be adjusted without necessitating the disassembling of the socket. The socket comprises spaced insulating blocks connected by standards. The cord guide is attached to one of these standards by soldering or formed integral therewith in any suitable manner. By constructing the guide in this manner the shell and cap inclosing the socket may be of the ordinary construction.

In the drawings: Figure 1 is an elevation of the lamp socket showing the shell and cap in section; Fig. 2 is a view of one of the insulating blocks; Fig. 3 is a view of the other insulating block; Fig. 4 is a view of the movable ratchet member; Fig. 5 is a 45 perspective view of the movable contact plate; and Fig. 6 is a sectional view of the socket along the line 6-6 of Fig. 3.

Referring to the drawings, 10 designates the upper insulating block and 11 the lower insulating block, these blocks being con-

nected by standards 13, 14 and 15. The standards 13 and 14 are provided with the usual binding screws forming the terminals of the lamp, and standard 13 is connected to the socket B which forms one of the lamp contacts by means of the screw 13'. The insulating block 11 is provided with inclines 16, 17, 18 and 19 forming teeth. These inclines are preferably segmental in form and formed integral with the block 11. The inclines 18 and 19 are provided with metallic facings secured thereto in any suitable manner, preferably by small pins or screws as shown. The plate on the face 19 is electrically connected with the standard 14 as shown in Figs. 3 and 6, and the contact face on the incline 18 has a downwardly extending portion 20 terminating in the second lamp contact 21.

A metallic contact plate 25 provided with radial arms 26 is provided with a hole 27 and rotatably mounted upon the pivot pin 28, which pivot pin is mounted in the insulating blocks 10 and 11. Pivoted upon the pin 28 is an operating member, preferably of insulating material, provided with ratchet teeth 30. A torsion spring 31 coiled on the pin 28 is connected at one end to the ratchet member 29 and at its other end to the T-shaped head 33 of the pin. The head is provided with a slot 32 so that it may be engaged by a screw-driver inserted through the hole 34 formed in the upper insulating block. This block is also provided with locking recesses 35 for engaging the arms of the T-shaped head 33 and maintaining it in position. The tension of the spring 31 may be adjusted by inserting a screw-driver through the hole 34 and moving the pin downwardly until the head 33 is out of engagement with the recesses 35. The pin may then be rotated until the desired tension has been obtained, and when released the head 33 will engage the locking recesses 35 and hold the pin against rotative movement. The ratchet member 29 is provided with a segmental portion 36 provided with a circumferential groove 37. A notched pin 38 is located in this groove and is adapted to engage the balls on the pull cord or chain 39. This chain passes through a flaring guide 40 secured to the standard 15 in any suitable manner and is preferably formed integral therewith. The inclines 16, 17, 18 and 19 are formed on an annular boss, and the in-

side diameter of this boss is substantially the same as the outside diameter of the ratchet member 29. By means of this construction the teeth on the separate members are prevented from interfering. The socket is enclosed by the usual shell 45 and the usual cap 46, and the usual insulation 47, 48 is provided.

In Figs. 1 and 3 the contact plate 25 is shown in a position in which the circuit is open. By pulling the cord 39 downwardly the ratchet member 29 is moved so that its teeth 30 engage the arms of the contact plate and move it one-fourth of a revolution until it snaps over the inclines 16 and 17 and drops into engagement with the switch contact faces upon the inclines 18 and 19, a firm contact being made due to the action of the spring 31 which, acting through the ratchet member 29, moves the contact plate 25 into engagement with the switch contacts. The contact plate 25 will thus bridge the switch contacts and the circuit will be closed. When the cord 39 is released the spring 31 will move the ratchet member back so that another set of teeth engage the arms 26. A second pull upon the cord 39 will open the circuit. It will be noted that the circuit is closed by bridging the switch contacts on the inclines 18 and 19 by means of a single contact plate 25. This construction has a decided advantage over those constructions in which the contact is made through the pivot pin, due to the fact that in the latter construction the contact between the pivot pin and the contact plate is more or less loose. In this construction, however, the current passes directly through the contact plate, and the spring 31 maintains this contact plate in firm engagement with the switch contacts. By securing the guide 40 to the standard 15 and by forming it integral therewith a rigid structure and bearing for the guide is obtained. This construction has a decided advantage over those constructions in which the guide is formed upon the shell. In the latter construction the guide is liable to break off when any strain is put upon it. In the construction shown in the drawing the shell and cap may be of the usual construction.

While this invention is shown as applied to a lamp socket it is obvious that certain features may be applied to any electrical switch, and it is therefore to be understood that this invention is not to be limited to a lamp socket.

It is obvious that various changes may be made in the details of construction without departing from this invention, and it is therefore to be understood that this invention is not to be limited to the specific constructions shown.

What we claim is:

1. In a lamp socket, the combination with

an insulating block and a pivot thereon, of a set of switch contacts arranged radially on said block and around said pivot, a ratchet member mounted on said pivot and having ratchet teeth facing in the opposite direction with respect to said switch contacts, and a movable contact plate mounted on said pivot between said block and ratchet member to be engaged by said ratchet teeth and adapted to bridge and connect said switch contacts. 70

2. In an electrical switch, the combination with an insulating block, of a set of oppositely disposed switch contacts mounted thereon, a movable contact plate having arms and adapted to bridge the switch contacts, a pivot pin for the contact plate, and a ratchet member mounted on the pivot pin and having teeth engaging the arms of the contact plate to operate the same. 80

3. In an electrical switch, in combination, an insulating block provided with pairs of inclines, the alternate inclines having switch contact faces, a movable contact plate adapted to bridge and be moved out of engagement with both of the switch contact faces said plate engaging said contact faces directly, and a ratchet member for operating the contact plate. 90

4. In a lamp socket, the combination with lamp contacts, of a terminal attached to one lamp contact, an insulating block provided with pairs of inclines, the alternate inclines having switch contact faces, and one of the contact faces being connected to the other lamp contact, a terminal connected to the other contact face, a contact plate bridging the contact faces, and a ratchet member having a tooth engaging the contact plate. 95

5. In a lamp socket, the combination with an insulating block, of lamp contacts mounted thereon, said block being provided with pairs of inclines, the alternate inclines having switch contact faces in series with the lamp contacts, a contact plate bridging the contact faces, and an operating ratchet member having a tooth engaging the contact plate. 105

6. In a lamp socket, the combination with an insulating block, of lamp contacts and terminals and a set of switch contacts mounted thereon, one of the switch contacts being connected to one terminal and the other to one of the lamp contacts, a movable contact plate adapted to bridge the switch contacts, and a ratchet member for operating the contact plate. 115

7. In an electrical switch, in combination, an insulating block provided with pairs of inclines, the alternate inclines having switch contact faces, a movable contact plate adapted to bridge the switch contact faces, a ratchet member having teeth engaging the contact plate to operate the same, the inclines on the block and the teeth on the 125

ratchet member being on circles of different diameters, for the purpose set forth.

8. In an electrical switch, in combination, an insulating block provided with pairs of inclines, the alternate inclines having switch contact faces, a movable contact plate adapted to bridge the switch contact faces, a ratchet member having teeth engaging the contact plate to operate the same, the teeth

on the ratchet member being located inside 10 of the inclines, for the purpose set forth.

In testimony whereof we affix our signatures in presence of two witnesses.

HARRY J. MOREY.
FAY A. BROGDEN.
